DESIGN FOR A COMBINED GEAR HOUSING AND SPINDLE SUPPORT FOR A LAUNDRY DEVICE

Fred A. Conterman, Jamestown, N. Y., assignor
to Blackstone Manufacturing Company, Inc.,
Jamestown, N. Y., a corporation of New York

Application October 7, 1939, Serial No. 87,562

Term of patent 7 years

To all whom it may concern:

Be it known that I, Fred A. Conterman, a citizen of the United States, residing at Jamestown, in the county of Chautauqua and State of New York, have invented and produced a new, original, and ornamental Design for a Combined Gear Housing and Spindle Support for a Laundry Device, of which the following is a specification, reference being had to the accompanying drawing, forming part thereof; and in which

The figure is a perspective view of a combined gear housing and spindle support for a laundry device, showing my new design.

I claim:

The ornamental design for a combined gear housing and spindle support for a laundry device, substantially as shown.

FRED A. CONTERMAN.
